UNITED STATES PATENT OFFICE.

OLIVER SHALLENBERGER ATTERHOLT, OF JERMYN, PENNSYLVANIA.

LAMP.

No. 858,251.

Specification of Letters Patent.

Patented June 25, 1907.

Application filed November 2, 1906. Serial No. 341,785.

To all whom it may concern:

Be it known that I, OLIVER SHALLENBERGER ATTERHOLT, a citizen of the United States, residing at Jermyn, in the county of Lackawanna and State of Pennsylvania, have invented a new and useful Lamp, of which the following is a specification.

This invention relates to illuminating lamps, and has for its principal object to provide an ornamental lamp body and globe arranged to carry a burner or the like, and in which an electrical current, oil or other material may be used as an illuminant.

A further object of the invention is to provide a lamp or lamp body which may be made in various ornamental designs and which is adapted to be constructed wholly of glass, it being unnecessary to employ metallic or other supports for the globe or shade.

A still further object of the invention is to provide a lamp including a separable body portion and globe in which the body portion is provided with a contracted neck arranged below the globe support, and serving as a means for supporting the burner element.

A still further object of the invention is to provide a lamp or lamp body in which the burner element is readily accessible for renewal, repairs, cleaning or adjustment.

With these and other objects in view, as will more fully hereinafter appear, the invention consists in certain novel features of construction and arrangement of parts, herein-after fully described, illustrated in the accompanying drawings, and particularly pointed out in the appended claims, it being understood that various changes, in the form, proportions, size and minor details of the structure may be made without departing from the spirit or sacrificing any of the advantages of the invention.

In the accompanying drawings:—Figure 1 is a sectional elevation of a lamp constructed in accordance with the invention. Fig. 2 is a similar view illustrating a slight modification of the structure. Fig. 3 is a still further modification embodying the invention.

Similar numerals of reference are employed to indicate corresponding parts throughout the several figures of the drawings.

In the construction shown in Fig. 1, the base or body 10 of the lamp is provided with a contracted neck 11 and outwardly flared top and bottom, the bottom being of greater diameter than the top and serving as a base on which the lamp may rest. The contracted neck 11 serves as a support for the burner element. In the present instance an incandescent lamp α is shown, the lamp being of ordinary construction and provided with a threaded end that is adapted to screw within a threaded socket 15 carried by the contracted neck 11, and the lamp being preferably extended upward into the globe 16. The globe 16 has a closed round top, and at the bottom is extended inward, and is provided with a depending annular flange 17 that seats within the top of the body portion or stand 10, the globe being firmly supported, and being held from lateral play. The globe may be readily removed when cleaning becomes necessary, or when it is desired to remove the lamp.

In the construction shown in Fig. 2, the body portion or stem is the same as that shown in Fig. 1, while the globe comprises an upper dome shaped portion 16^a and a lower or base portion 16^b, which latter is provided with the depending flange 17 that fits within the top of the base or burner carrier. At the outer edge of the base portion 16^b is a vertically disposed flange 18, within which the lower edge of the upper portion of the globe is seated.

In the construction illustrated in Fig. 3, the base member 10' has its top portion extended and of much greater diameter than the bottom, and this top portion is provided with a flange 21 that extends around a seat on which the upper portion 22 of the globe may be arranged, the structure in this case following generally the contour of an acorn.

While the lamp and globe may be made of any desired material, the construction is such that cut, pressed or blown glass may be used for both the body and globe without the necessity of employing any metal trimmings or supports for the globe proper.

I claim:—

A lamp having separable base and globe

elements, the former being centrally open from top to bottom and having its bore contracted at an intermediate point to engage a burner element, and the globe element being closed at the top and having an open bottom, and a depending edge seating within the upper edge of the base element.

In testimony that I claim the foregoing as my own, I have hereto affixed my signature in the presence of two witnesses.

OLIVER SHALLENBERGER ATTERHOLT.
